McNatt & Owen Atty:

UNITED STATES PATENT OFFICE

SIMEON C. LAWLOR, OF CHICAGO, ILLINOIS

WINDOW POLE

Application filed January 6, 1930. Serial No. 418,806.

My invention relates in general to an improved window pole and more specifically to an improved type of pole having certain features of improvement in design which render 5 the new pole more useful and less liable to cause damage to window glass in opening and closing.

The main feature of the invention is to provide a pivoted metal hook on the end of 10 the pole which is normally held in operative position by a spring, and which spring gives a cushion effect so that the metal hook will not as readily cause glass breakage.

The pivoted hook in its normal position 15 may be readily hooked over a molding hook or like projection in order to hang up the hook when not in use, and due to its pivot and the spring cushion, recedes to a position where it is more useful in opening a window.

20 Further features and objects will be apparent from the following detailed description in which reference may be had to the accompanying sheet of drawings.

Fig. 1 is a side view of the improved window pole with certain parts cut away to 25 more clearly illustrate the same.

Fig. 2 is a view taken from the left of Fig. 1.

Fig. 3 is a view taken from the top of 30 Fig. 1.

Fig. 4 is a detail view showing the position of the spring cushion.

Fig. 5 is a detail view from the top with the hook removed showing the position of 35 the spring.

Referring to Fig. 1 I have disclosed a metal head 1 having a socket at the lower end into which a wood handle 2 is inserted and riveted by a metal rivet 3. On the head 40 1 is a projecting rim 4 which supports a rubber cushion 5. This rim 4 is longer in the front to prevent breakage of windows in use. Above the rim 4 are a pair of lugs 6 into which is inserted a metal hook 7 which is 45 formed in the shape of a goose neck, the upper end being formed with a ball projection 8 for insertion into the socket at the upper sash of a window for opening the same. On the upper surface the hook 7 has a flat surface 50 9 so that it may be used under the win-

dow sash if desired to push the window up. The hook 7 is pivoted to lugs 6 by means of a rivet 10 and has a limited movement back and forth. On the metal head 1 and between the lugs 6 is a slot 11 in the surface of the metal, and a corresponding slot 12 in the lower surface of hook 7. Into these slots are inserted the ends of a spring 13, each end of the spring 13 being bent outward and thus held in position and its tension normally tending to hold the hook 7 in the position shown in full lines in Fig. 1. This permits the hook 7 to move backward to the position shown in dotted lines when pressed against any object such as the window sash.

It will thus be seen that the hook 7 is held forward by spring 13 in the position such that it can readily be hung up by hooking the curved end over a molding or like projection while not in use. In this position, as 70 shown by the full lines in Fig. 1, the hook is forward so that the pole will hang in as near as possible in a vertical position when hung on a molding even though the rubber bumper 5 projects farther from the front of the pole.

In use to operate a window, however, the pole may be held out from the window at an angle and the tip 8 of the hook inserted into the usual hole in the upper sash of the window. The tension of spring 13 75 will in this case be overcome to a certain extent and the window may be operated with ease.

In addition to providing a pivoted hook which has the two alternate positions, one for use in hanging up the pole and the other for operating the window, the spring 13 acts as a cushion for the hook 7 so that in attempting to operate a window if this metal hook should accidentally strike the window glass it will give against the tension of spring 13 and not strike the glass with such force as if the hook were fixed.

The wooden handle 2 shown broken away in Figs. 1 and 2 may be of any desired length or size as conditions require. It will also be understood that any type of spring may be used to hold the hook in place of spring 13, such expedients as coil springs or leaf springs being well known and spring 13 being shown only to illustrate the invention.

Having thus fully described the features and objects of my invention, what I consider to be new and desire to have protected by Letters Patent will be pointed out in the appended claims.

What is claimed is:

1. A window pole comprising a handle, a metal head on one end thereof, a metal hook pivoted on said metal head, and a spring normally maintaining said hook in forward position.
- 10 2. A window pole comprising a wood handle, a metal head secured to one end of the handle, a pair of lugs on the head, a goose neck metal hook riveted between said lugs and having a limited movement forward and backward.
- 15 3. A window pole comprising a wood handle, a metal head on one end of the handle, a ridge of metal extending outward around said head, a rubber bumper mounted on said ridge, a metal hook riveted to said head and having a limited forward and backward movement.
- 20 4. A window pole comprising a wood handle, a metal head on one end of the handle, a ridge of metal extending outward around said head, a rubber bumper mounted on said ridge, a metal hook riveted to said head and having a limited forward and backward movement, and a spring for maintaining the hook in its forward position normally.
- 25 5. A window pole comprising a wood handle, a metal head on one end of the handle, a pair of lugs extending upward from the head, a hook riveted between said lugs and having a limited forward and backward movement, a rubber bumper mounted on the head and extending outward around the same, a leaf spring inserted in place between the base of the hook and the metal head, said spring normally retaining the hook in its extreme forward position for hanging the pole on a molding or the like, and acting as a cushion when the hook is used to open or close a window.

In witness whereof, I hereunto subscribe my name this 3rd day of January, A. D. 1930.
